UNITED STATES PATENT OFFICE.

WILLIAM D. COMBS, OF CANON CITY, COLORADO.

WASHING-MACHINE.

932,759.

Specification of Letters Patent. Patented Aug. 31, 1909.

Application filed July 7, 1908. Serial No. 442,329.

To all whom it may concern:

Be it known that I, WILLIAM D. COMBS, a citizen of the United States, residing at Canon City, in the county of Fremont and State of Colorado, have invented certain new and useful Improvements in Washing-Machines; and I do hereby declare the following to be a full, clear, and exact description of the invention, such as will enable others skilled in the art to which it appertains to make and use the same.

This invention relates to new and useful improvements in washing machines and it is an object of the invention to provide a novel device of this character wherein the articles to be cleansed may be agitated within the washing fluid in such a manner as to permit a thorough percolation or penetration of the washing fluid and air through the articles to be cleansed to assure the removal of all foreign substances from the articles.

The invention also has for an object to provide a novel device of this character wherein is employed a reciprocating holding member, said member being operated by mechanism exterior of the washing fluid container.

It is also an object of the invention to provide a novel device of this character which will be simple in construction, efficient and advantageous in practice and comparatively inexpensive to manufacture.

With the above and other objects in view the invention consists in the details of construction and in the novel arrangement and combination of parts to be hereinafter more particularly referred to.

In describing the invention in detail reference will be had to the accompanying drawings forming part of this specification wherein like characters of reference denote corresponding parts in both views, and in which,

Figure 1 is a view partly in section and partly in elevation illustrating one form of invention, and, Fig. 2 is a similar view illustrating a second form of invention.

In the drawings 1 denotes a liquid container or tub of any ordinary or preferred construction, having the closure 2 for the top or open end thereof. This closure may be as desired, but it is preferred that it be formed in two sections, the opposed edges of the sections approximately centrally thereof being provided with elongated recesses 3 which, when the sections of the

closure are assembled form an elongated opening for the passage of the rod 4. This rod 4 at its upper end is pivotally secured to a depending ear 5 formed with an end 60 portion of a lever 6. This lever 6 is pivotally secured intermediate its length by the pin 7 to the upstanding brackets 8 positioned adjacent one end of the tub 1. The end of the lever 6 opposed to that having the 65 ear 5 is formed into a socket 9 for the reception of an operating handle 10.

It is thought to be apparent that it is the object of the invention to oscillate the lever 6 so that the rod 4 may be reciprocated, the 70 elongated opening formed by the recesses 3 permitting sufficient lateral play of the rod 4 to assure its movement. For convenience in operation the lever 6 has positioned adjacent its pivotal connection with the brackets 8 75 and extending at right angles to the lever a second socket 11, as is believed to be apparent.

The lower end portion of the rod 4 has affixed thereto a spider 12, and approximately 80 centrally thereof the rod has secured thereto a second spider 13 and it is between the spiders 12 and 13 that the articles to be cleansed are inserted.

In the operation of the device the tub 1 is 85 filled with sufficient washing fluid as to extend above the upper spider 13 when the rod 4 is in approximately its lowermost position. Through the medium of the handle 10 and the lever 6 the rod 4 is caused to reciprocate, 90 said reciprocation withdrawing the articles between the spiders 12 and 13 partially without the fluid, thereby permitting not only a percolation or penetration of the washing fluid but of air which together with the 95 action of the fluid assures the removal of all foreign substances from the articles, in other words it is to be stated that the present invention performs its function by an agitation of the articles to be cleansed within 100 both a washing fluid and the atmosphere.

In Fig. 2 is illustrated a form of invention somewhat similar as disclosed by Fig. 1 except that the reciprocating rod 14 is provided with but one spider 15, secured to its lower end portion. In lieu of the second spider the closure 16 of the tub 17 is provided with depending spiral springs 18, the articles to be cleansed being positioned on the spider 15 and adapted to contact with the lower 105 fakes of the springs in the upward movement of the spider, the compression of the

springs causing a rebound or return of the articles.

When the form of invention disclosed in Fig. 2 is employed it is necessary that the closure 16 be assured against displacement. This may be done in any manner, but as illustrated in the drawings a sufficient number of cross-bars 19 are employed, said cross-bars 19 projecting beyond either side of the tub 17, said projected portions being provided with depending eyes 20 engaged by hooks 21 pivotally secured to the sides of the tub.

I claim:

A device of the character described, comprising a receptacle having a closure, a number of helical springs suspended from the under side of said closure and depending within said receptacle, with their lower ends arranged a short distance from said closure,

a vertically reciprocable rod within said receptacle carrying a spider at its lower end, and means for actuating said spider carrying rod, said springs adapted to have contact with, and be compressed by the action of the contents of said receptacle, as said contents are lifted by said spider at the upward movement of said rod having the effect to expedite and render automatic the downward movement or stroke of said rod with its spider-member.

In testimony whereof I have signed my name to this specification in the presence of two subscribing witnesses.

WILLIAM D. COMBS.
